UNITED STATES PATENT OFFICE.

ALBERT A. COON, OF HUTSONVILLE, ILLINOIS.

GATE.

1,174,477.

Specification of Letters Patent.

Patented Mar. 7, 1916.

Application filed January 27, 1915. Serial No. 4,764.

To all whom it may concern:

Be it known that I, ALBERT A. COON, a citizen of the United States, residing at Hutsonville, in the county of Crawford and State of Illinois, have invented certain new and useful Improvements in Gates, of which the following is a specification.

This invention relates to farm gates and more particularly to an improvement in supports for gates of the swinging folding panel type. Gates of this type are so constructed that their latch or free ends may be elevated so as to permit of the gate being swung over snow drifts or up hill or to permit of the passage of hogs, sheep, and the like, and yet prevent the passage of cattle.

It is the aim of the present invention to provide a support for a gate of this type so constructed as to act automatically to support or brace the gate in any position to which it may be adjusted, the support being furthermore so constructed as to securely lock in its various positions of adjustment in such manner that it will not be liable to become accidentally disarranged or released.

Another aim of the invention is to so construct the support that it may be readily manipulated to permit of the free end of the gate being lowered.

The invention also aims to provide a support so constructed that the weight of the gate imposed upon it will result in a direct pull being exerted by the support through the free end of the gate toward the hinged end thereof, so that warping of the gate and stiles is prevented.

In the accompanying drawings: Figure 1 is a view in elevation of the gate embodying the present invention, the gate being shown in one position in full lines and in another position in dotted lines. Fig. 2 is a vertical sectional view through the gate on the line 2-2 of Fig. 1. Fig. 3 is a vertical longitudinal sectional view through a portion of the support for the gate. Fig. 4 is a perspective view of one member of the support.

Corresponding and like parts are referred to in the following description and indicated in all the views of the accompanying drawings by the same reference characters.

In the drawings, the numeral 1 indicates the bars of the gate, the numeral 2 indicates the stiles at the hinged end of the gate, 3

the stiles at the latch end of the gate, and 4 the intermediate stiles. The bars 1 are arranged in parallel relation with respect to each other and are pivoted between the stiles 2 and to the stiles 3 and 4 by means of bolts 5. This is the usual arrangement of the bars and stiles of a gate of the type mentioned above and it will be understood that the latch end of the gate may be tilted or elevated with respect to the hinged end thereof and may likewise be lowered. Fitted through the stiles 2 near the upper ends thereof is a bolt 6 to which is connected a pintle lug or eye 7 comprising a member of the upper hinge for the gate, this eye being engaged with the usual pintle, indicated at 8, carried by the hinge post. The lower hinge for the gate will be presently specifically described. Pivoted at their upper ends to the bolt 6 are two bars 9 comprising members of the supporting device embodying the present invention. These bars extend at opposite sides of the gate as clearly shown in Fig. 2 of the drawings and furthermore extend diagonally downwardly toward the lower corner of the gate at the free end thereof. The supporting device further includes a dog member and a keeper bar.

The keeper bar is indicated by the numeral 10 and is preferably circular in cross section and is pivotally connected, as at 11, to a bolt extending between two of the stiles 3. The bar 10 extends between two of the bars 1, as clearly shown in Fig. 1 of the drawings. The dog member is clearly shown in Figs. 3 and 4 of the drawings, and comprises a plate 12 which is preferably relatively thick and is formed with an opening. The lower end of the plate is rolled upon itself, as at 14, to form a sleeve in which is fitted a bolt 15 to which are pivoted the lower ends of the bars 9. At its upper end the plate 12 is bent to form a handle extension 16 which extends approximately at right angles to the plate 12 and beyond that face thereof opposite the face at which the sleeve 14 is located.

By reference to Figs. 1 and 3 of the drawings, it will be observed that the keeper bar 10 is fitted through the opening 13 in the dog member, and by reference to Fig. 3 it will be observed that when the weight of the gate is imposed upon the supporting device the dog member will be canted so that the edges

of the wall of the opening 13 will bite into the bar 10. By reason of this engagement of the dog with the bar 10, the dog will be held against movement along the bar and 5 the gate will be supported in the position to which it has been adjusted. It will be understood that in order to adjust the gate, and have the same supported in the position to which it is adjusted, it is only necessary to 10 elevate the latch end of the gate. In doing this, the dog will slide along the bar in the direction of the pivoted end thereof and when the gate is released the dog will automatically grip the bar and the gate will be 15 held in adjusted position. When it is desired to lower the gate, the latch end thereof is slightly elevated and the handle 16 of the dog is grasped and the dog is tilted so as to bring the edges of the wall of the opening 20 13 out of engagement with the bar. The dog being held in this position, the gate may be lowered to the desired position, the dog in the meantime sliding freely along the bar and, when the gate has been properly positioned, the dog is released and will automatically 25 grip the bar.

From the foregoing description of this portion of the structure, it will be apparent that the bars 9 being connected to the bolt 6 30 exert, through the medium of the dog, a direct pull upon the keeper bar 10 substantially in a line parallel to the bars 1 of the gate, and it will furthermore be understood that, inasmuch as two of the bars 9 are provided and are located at opposite sides of the gate, the gate is prevented from warping or becoming otherwise distorted.

Having thus described the invention, what is claimed as new is:

40 1. The combination with a gate of the swinging, vertically foldable panel type, of a supporting device for the gate including a keeper bar pivotally connected to the gate at the free end thereof, a brace bar pivotally connected at one end to the hinged end of

the gate, and a dog pivotally connected to the other end of the said brace bar and provided with an opening receiving the said keeper bar, the opposite edges of the wall of the opening engaging the said keeper bar 50 when the dog is canted.

2. The combination with a gate of the swinging, vertically foldable panel type, of a supporting device for the gate including a keeper bar connected to one of the stiles of 55 the gate at the free end thereof, a brace bar connected at one end to one of the stiles of the gate at the hinged end thereof and extending downwardly at an angle in the direction of the said keeper bar, and a dog 60 pivotally connected to the lower end of the said brace bar and having an opening to receive the keeper bar, the opposite edges of the wall of the opening engaging the said keeper bar when the dog is canted, and a 65 handle carried by the dog above the said keeper bar.

3. The combination with a gate of the swinging, vertically foldable panel type, of a supporting device for the gate including a 70 keeper bar connected to one of the stiles of the gate at the free end thereof, a brace bar connected at one end to one of the stiles of the gate at the hinged end thereof and extending downwardly at an angle in the direction of the said keeper bar, and a dog 75 comprising a body pivotally connected to the lower end of the brace bar and provided above its pivot with an opening receiving the keeper bar, the upper end of the said 80 body being turned at an angle to form a handle extending above the said keeper bar, the opposite edges of the wall of the opening in the dog engaging the keeper bar.

In testimony whereof I affix my signature 85 in presence of two witnesses.

ALBERT A. COON. [L. S.]
